UNITED STATES PATENT OFFICE.

ERNST BRINKMANN, OF BRESLAU, GERMANY.

PAINTING OR WHITEWASHING PUMP.

No. 894,112.

Specification of Letters Patent.

Patented July 21, 1908.

Application filed October 21, 1905. Serial No. 283,800.

To all whom it may concern:

Be it known that I, ERNST BRINKMANN, a subject of the King of Prussia, and residing at Breslau, Prussia, Germany, have invented 5 certain new and useful Improvements in Painting or Whitewashing Pumps, of which the following is a description.

The present invention relates to pumps for painting or whitewashing purposes and consists of the details of construction herein-after set forth and particularly pointed out in 10 the claim.

The accompanying drawing shows a side elevation of the pump with the bucket in section.

A pump *b* of any suitable known construction, advantageously having the cylinder moved up and down over the plunger *e* and plunger rod *d*, is provided with the perforated 20 suction head *c* which opens into the hollow rod *d*. The delivery pipe *f* leads to a delivery head in known manner. The handle *a* of the pump cylinder *b* is of the form indicated in the detached view. One of the staves of the 25 bucket *g* is prolonged upwardly, or a special post *m* may be provided to the top of which a lever *i* is pivoted at *l*. This lever simply rests on the handle *a*, and its movement upwardly is limited by a stop *o*, the downward 30 movement being limited, as will be self evident by the stroke of the pump and the play

for the handle is limited by stops *n* on the under side of the said lever, which is provided with a handle *k*. The cylinder is returned to its upper position after depression 35 by means of the spring *d'*. The plunger is rigidly supported at *h* on the bottom of the bucket on to which the pump fits.

In operation an ordinary garden or whitewashing pump is fitted on to the socket and 40 worked by means of the lever and the returning spring as will be readily understood on reference to the drawing.

I claim as my invention:—

A device for painting or white washing consisting of a bucket having the stationary part of a pump fixed at its bottom, a fixed arm at the side of the bucket, extending substantially vertically upwardly, a lever arm hinged to the upper end of said fixed arm, an 45 antifriction device fixed to the upper part of the movable member of said pump and upon which said lever arm unconnectedly rests and stops on the latter, to limit the play of the said antifriction device against the said 50 lever, substantially as described.

In testimony whereof I affix my signature in the presence of two witnesses.

ERNST BRINKMANN.
